Application October 23, 1953, Serial No. 393,072

8 Claims. (Cl. 333—7)

The present invention is related to duplexers, and particularly to duplexers operative in the microwave frequency region.

Microwave duplexers are well known. Their function may be described in connection with pulsed radar (radio echo detection and ranging) systems. In these systems, a microwave generator transmits pulses of radio frequency energy under control of a pulse modulator. The energy is applied to an antenna through a transmission line. At a branch point the transmission line leads to a receiver. The duplexer may include a TR (transmit-receive) and ATR (anti-transmit-receive) arrangement. These operate to connect the antenna to the generator under transmit conditions and disconnect the receiver. Under non-transmit conditions, the duplexer connects the antenna to the receiver and disconnects it from the transmitter. This function may be performed by a simple TR switch positioned at the proper distance from the branch point toward the receiver, and the branch point must be properly positioned. Additionally, an ATR (anti-transmit-receive) switch may be inserted in the transmission line between the transmitter or microwave generator and the branch point. When an ATR switch is used, the branch point position in relation to the generator (excluding the ATR) is not so important. At high power levels, it is sometimes useful to use a pre-TR switch or tube which aids the TR switch in reflecting energy which might otherwise pass to the receiver.

The various switches employed as TR, ATR, and pre-TR switches usually take the form of a resonant circuit coupled with a gas discharge tube. Sometimes, these components may be used interchangeably, that is, a component which in one case serves as a TR tube may in another case serve as a pre-TR tube. However, it is not convenient to employ TR switches which are designed for use with hollow pipe waveguide with coaxial line waveguide. On the other hand, it is sometimes inconvenient to use hollow pipe waveguide, because such waveguide is too bulky at the design frequency for the proposed use. Coaxial line is more compact, but does not have the power carrying capacity. However, if standard coaxial line waveguides are to be employed at microwave frequencies with TR components commercially available and of the type suited for hollow pipe waveguide, then a transition must be designed in order to enable the use of the standard component. Such transitions usually are space consuming. On the other hand, coaxial line pre-TR tubes are not available. Therefore, under certain design requirements, it becomes desirable to employ the hollow pipe waveguide pre-TR tube and other TR components with a coaxial line system.

It is an object of the present invention to provide a TR arrangement which is compact and uses standard hollow pipe waveguide components in conjunction with coaxial line waveguide.

Another object of the invention is to provide a TR, pre-TR arrangement employing hollow pipe waveguide components but associated with coaxial line waveguide.

A further object of the invention is to employ hollow pipe waveguide TR components in conjunction with coaxial line waveguide with a saving of space and a compact arrangement.

5 In accordance with the invention, at the junction between the receiver transmission line and the coaxial transmission line from transmitter to antenna, a compact transition section from coaxial line to hollow pipe waveguide is inserted. At this junction point, a pre-TR switch is inserted. Notwithstanding that the compact pre-TR arrangement and its transition is mismatched at the high microwave frequency at which it is to operate, a TR cavity arrangement interposed close to the pre-TR switch in the line to the receiver is tuned in such a way 15 that the entire circuit is resonant at the desired operating frequency, and the mismatch of the pre-TR switch is tuned out by the TR cavity tuning.

The foregoing and other objects, advantages and novel features of the invention will be more fully apparent 20 from the following description when taken in connection with the accompanying drawing, in which like reference numerals refer to like similar parts, and in which

25 The sole figure is a diagram, schematically portraying a radar system in which the invention may be embodied, and showing in cross-section the TR and pre-TR arrangement according to the invention.

Referring to the drawing, the transmitter may include a magnetron transmitter 10 under control of a pulse modulator 12. The transmitter 10 is connected to apply 30 energy through an ATR switch 14 and a transmission line 16 to an antenna 18 which may have directional characteristics and be directed as desired. The transmission line 16 is a coaxial transmission line or coaxial waveguide. It must handle substantial amounts of power, 35 but conservation of space is in this instance very important. The pre-TR, TR arrangement 20 includes a TR switch 22 and a pre-TR switch 24 coupled by a short section of rectangular hollow pipe waveguide 26. The junction A between the pre-TR, TR arrangement 40 20 and the coaxial waveguide 16 is made by a transition 28 from coaxial line to hollow pipe waveguide. The hollow cavity resonator 30 of the TR switch 22 is coupled to the receiver 32 by a coupling loop 34 through a coaxial line.

45 The operation of the system as a whole may be understood from the foregoing. The general operation of such systems is well explained in "Radar System Engineering" edited by Ridenour, vol. 1 of the Radiation Laboratory Series published by McGraw-Hill section 11.5, page 407. Reference may also be made to "Microwave Receivers" edited by Van Voorhis, vol. 23 of the Radiation Laboratory Series, chapter 2 beginning at page 5. When the magnetron 10 transmits under control of the pulse modulator 12, the ATR, pre-TR, and TR 50 switches are fired. The transmitter 10 is then connected to the antenna. The branch line to the receiver 32 is "blocked" because of the short circuit effectively across this branch line because of the firing of the TR and pre-TR switches. The energy therefore passes to the antenna, and is prevented from passing to the receiver.

The ATR switch 14 in this particular equipment is effectively in series with the coaxial waveguide 16, and is spaced effectively three quarters wavelength from the junction A. Therefore, when the magnetron or transmitter 60 10 is in the non-transmit condition under control of the pulse modulator 12, energy from the antenna 18 passing along the coaxial waveguide 16 is blocked at the junction A looking in the direction of the magnetron 10. In the direction of the receiver, however, neither the 65 pre-TR switch 24 nor the TR switch 22 is fired, and energy passes to the receiver as though the coupling were direct, and the pre-TR and TR arrangement 20 were not

interposed. The function of the pre-TR switch 24 is readily explained in that when there is high powered transmission the TR switch alone and by itself is insufficient to prevent damage to the receiver. Accordingly, it is often desirable to insert a pre-TR switch. This pre-TR switch is usually inserted between the TR switch and the junction. The pre-TR switch may be placed substantially at the junction, and is spaced from the TR switch, for a reason explained hereinafter.

In greater detail, the coaxial transmission line is modified at the point where the junction is to be made by enlargement of the outer conductor over a substantial length. The enlargement is made over approximately a half portion on one side of a radial plane through the axis of the coaxial line. Thus, as viewed in the figure, the enlargement is made in the upper portion of the outer conductor of the coaxial line 16. The enlarged portion thus has side walls 36 and continuity with the remainder of the outer conductor is maintained by including partial bottom walls 38 to complete the section 26 of rectangular hollow pipe waveguide, the longitudinal axis of which is at right angles to the longitudinal axis of the coaxial waveguide 16, and having an end opening contiguous with half of a cylinder formed by the outer conductor of line 16. The inner conductor 40 of the coaxial waveguide 16 may also be enlarged at the point where the outer conductor is enlarged to improve the match during transmission. The rectangular waveguide section 26 includes a part 54 provided with a flange 42 having pins 44 threaded into suitably drilled holes (not shown) to hold the portion 54 in place. A pair of metal gaskets 46, and 48 are provided which grasp between them the metal plate 50 of the pre-TR switch 24. A pre-TR tube 52 is mounted in a resonant aperture in the plate 50. The hollow pipe waveguide section 26 formed by the rectangular sidewalls 36 is continued by the gaskets 46 and 48 and by the further portion 54 until it merges into a cavity resonator 56. The cavity resonator 56 is part of the TR switch 22 which includes the TR tube 58. The TR tube is mounted in a standard fashion and has a tuning mechanism actuated by rotation of a shaft 60. It is contemplated that the shaft 60 may be remotely adjusted by means of a flexible rotatable shaft. As understood in the art, the shaft 60 controls the spacing of a pair of keep-alive electrodes within the tube which in turn vary the resonant frequency of the cavity resonator 56. The TR tube 58 is a standard type modified by removing its tuning knob and mechanically coupling the rotatable shaft to the knob shaft. The coupling loop 34 is located on the side of the cavity resonator 56 remote from the side into which the waveguide section 54 leads. The coupling loop 34 leads to a coaxial transmission line 62 which makes a right angle turn at 64 and leads to a crystal inserted in the transmission line at 66. Only the crystal cartridge 68 is shown, the crystal and its contact within the holder (not shown) being well known in the art.

The coaxial transmission line 62 has an inner conductor 80. The inner conductor 84 of a section of coaxial transmission line 86 is coupled by a capacitive coupling 82 in the form of a disc closely spaced to the inner conductor 80. The transmission line 84 also makes a right angle turn, but is so arranged that the spacing of the capacitive coupling disc of coupling 82 in relation to the inner conductor 80 may be varied by a nut 88 and locked in place by a cooperating lock nut 90. The coaxial transmission line 86 leads to an ordinary type of coaxial line connector 92 for ready connection to a local oscillator (not shown).

In operation, it is well to bear in mind that the operating frequency may be 1300 mc. (megacycles per second). Because of the high transmitted power in this system, it is essential that a pre-TR switch be employed. Such a great amount of energy is fed through to the receiver during transmit periods, if only a TR switch is employed,

that damage to the receiver, e. g., crystal burn-out, results. At the frequency of operation, however, a pre-TR tube or pre-TR switch is available as a standard component only for hollow pipe waveguide. Moreover, to design a pre-TR tube for coaxial waveguide would require not only considerable engineering skill but would be very difficult. However, using the transition section made by enlarging the outer conductor of the coaxial line 16 into a rectangular hollow pipe waveguide section with sidewalls 36, the standard hollow pipe waveguide pre-TR tube 52 and the standard switch 24 may be inserted into this section of rectangular hollow pipe waveguide, which is then continued into the waveguide section 26. Unfortunately, this coupling or transition section 28 does not provide a good match at the operating frequency, during reception. Notwithstanding, a match at the operating frequency during reception may be secured by suitably tuning the tube 58. In transmission, a good receiver protection is secured by spacing the pre-TR and TR tube theoretically a quarter-wavelength. In practice, the spacing is made slightly different, in this case less than a quarter wavelength, in order to secure good results with a matched condition during reception. This departure from a quarter wavelength did not cause excessive leakage to the receiver during transmission. Although the transition 28 into the rectangular waveguide provides only a poor match to the receiver through the pre-TR resonant aperture, the tuning of the TR cavity and the proper spacing compensate for the transition mis-match, and the unit as a whole give proper and highly desirable operation. The unit 20 is, in fact, much more compact than many other systems which are provided with a proper matching section for the transition selected from among those which are known.

During transmit conditions the pre-TR tube 52 is fired and with the plate 50 provides a substantially continuous end wall to the enlarged rectangular cavity transition 28. Feed through to the crystal is further prevented by the firing of the cavity resonator tube 58 in the cavity resonator 56.

The following tube types may be employed: For the pre-TR tube 52, a type WL6260; for the TR tube 58, a type BL25. Although the ATR tube is not shown in detail it may be an arrangement similar to that illustrated in Fig. 2.50a of section 2.10 of chapter 2 of "Microwave Duplexers" edited by Smullin and Montgomery, vol. 14 of the Radiation Laboratory Series, and also employing a type BL25 TR tube.

In view of the foregoing, it will be apparent that the invention provides an especially compact pre-TR and TR arrangement for microwave frequencies for high power transmission. The arrangement includes an enlarged outer conductor transition section of coaxial line leading into a short section of hollow pipe waveguide in which is inserted a pre-TR tube in the form of a plate obstructing the waveguide transition section but having a resonant aperture in which is located a low pressure gas tube, readily ionized by high frequency energy. The hollow pipe waveguide continues beyond the plate obstruction to terminate in a cavity resonator of cylindrical conformation in which a suitable TR tube is inserted, and a coupling loop couples the cavity resonator to a receiver. If desired, the feed-in of the local oscillator and the crystal may be considered as a part of the receiver although separately shown in the figure.

What is claimed is:

1. A transmit-receive arrangement comprising a coaxial line section having inner and outer conductors, said outer conductor having a portion thereof expanded and enlarged into a rectangular hollow pipe waveguide section, and a transit-receive switch at the termination of said hollow pipe waveguide section remote from said outer conductor and coupled thereto, a pre-transmit-receive switch in said hollow pipe waveguide section spaced an odd multiple, including unity, of quarter wavelengths

from said transmit-receive switch, said hollow pipe waveguide section and pre-transmit-receive switch being mismatched to said coaxial line section at the operating frequency, said transmit-receive switch being tuned to compensate for said mismatch.

2. A transmit-receive arrangement comprising a coaxial line waveguide section having an inner conductor and an outer conductor, a section of hollow pipe waveguide, and a cavity resonator, said hollow pipe waveguide section having one end coupled to said coaxial line waveguide through an enlarged outer conductor portion thereof, and the other end coupled to said cavity resonator, said hollow pipe waveguide having at said one end a pre-transmit-receive switch spaced an odd multiple, including unity, of quarter wavelengths from said cavity resonator, said transition and said pre-transmit-receive being mismatched at the operating frequency, said cavity resonator being tuned to compensate for said mismatch and to match said transition section and said pre-transmit-receive together with said resonator at said operating frequency.

3. The transmit-receive arrangement claimed in claim 2, said pre-transmit-receive switch comprising a metallic plate obstructing said hollow pipe waveguide, and having a resonant aperture with a low pressure gas tube mounted in said aperture.

4. The transmit-receive arrangement claimed in claim 2, said inner conductor having a portion of radius enlarged over the radius of adjacent portions thereof, said enlarged radius portion being substantially coextensive along the length of the line with said enlarged outer conductor portion.

5. The transmit-receive arrangement claimed in claim 2, the coupling of said hollow pipe waveguide section to said cavity resonator comprising the termination of said section in an opening communicating directly with the 35 resonant cavity of said resonator.

6. The transmit-receive arrangement claimed in claim 5, said inner conductor having a portion of radius enlarged over the radius of adjacent portions thereof, said enlarged portion being substantially coextensive along the length of said coaxial waveguide with said enlarged outer conductor portion.

7. A transmit-receive arrangement comprising a coaxial line waveguide for connecting a transmitter and an antenna and having an inner conductor and an outer conductor, a hollow pipe waveguide branching from said coaxial line waveguide outer conductor at a junction, a pre-transmit-receive switch in said hollow pipe waveguide at said junction, a transmit-receive switch in said hollow pipe waveguide remote from said junction, said pre-transmit-receive switch alone being mismatched at the operating frequency, said transmit-receive switch being tuned to compensate for said mismatch, a further waveguide for connection to a receiver, said further waveguide by the tuning being coupled with a matched coupling at the operating frequency to said coaxial line waveguide by said hollow pipe waveguide during non-transmit periods of the transmitter.

8. The transmit-receive arrangement claimed in claim 7, said transmit-receive and said pre-transmit-receive switches being spaced apart slightly less than one quarter wavelength measured at said operating frequency.
